UNITED STATES PATENT OFFICE.

EDWARD A. BEACH, OF ALTOONA, PENNSYLVANIA.

VEGETABLE OR FRUIT STRAINER.

960,248.

Specification of Letters Patent. Patented June 7, 1910.

Application filed February 7, 1910. Serial No. 542,491.

To all whom it may concern:

Be it known that I, EDWARD A. BEACH, a citizen of the United States, residing at Altoona, county of Blair, State of Pennsylvania, have invented certain new and useful Improvements in Vegetable or Fruit Strainers, of which the following is a specification, reference being had therein to the accompanying drawing.

10 This invention relates to a fruit strainer or colander and particularly to an improvement upon my Patent #610,789, dated September 13, 1898.

15 The invention has for an object to provide a novel and improved construction comprising a holding frame to which both the receptacle and sieve are removably attached and adapted to be locked in their position thereon.

20 Other and further objects and advantages of the invention will be hereinafter set forth and the novel features thereof defined by the appended claims.

25 In the drawing—Figure 1 is a perspective showing the parts of the invention separated; Fig. 2 is a vertical section through the parts assembled; and Fig. 3 is a detail side elevation of the locking latch.

30 Like numerals of reference refer to like parts in the several figures of the drawings.

The numeral 10 designates the holding frame which comprises an annular rim having thereon a series of bayonet joints 11 disposed at different points and a supporting handle 12 extended laterally therefrom. This frame is provided with a supporting flange 13 for the rib 14 carried by the band 15 to which the sieve or screen 16 is secured. For the purpose of preventing rotation of this screen, it is provided with a pin 17 adapted to seat in a recess 18 in the holding frame 10.

40 The receptacle 19 is secured to the holding frame by means of the lugs 20 which enter the bayonet joints 11 and may be secured therein against rotation by means of a latch 21 pivoted upon the receptacle 22 and adapted to enter a recess 23 upon the holding frame 10 as shown in Fig. 3. This permits 50 the removal of either the screen or receptacle from the frame.

45 The receptacle 19 is provided with a supporting arm 25 having a bearing 26 for the shaft 27 of the stirrer 28. This shaft is 55 provided at its upper end with a crank 29 by which it may be operated. The shaft 27

is formed at its lower end with bifurcated arms 30 between which a stirrer blade 31 may be mounted. These arms are also provided with a lateral aperture 32 within 60 which a loosely mounted stirrer blade 33 is disposed and extends through an aperture in the stirrer blade 31. The stirrer shaft 27 is provided with an angular portion 34 which permits its removal from the support 65 25 through the aperture 35 therein. The lugs 20 on the receptacle 19 are suitably beveled so as to draw the parts in close contact when shifted within the bayonet joints 11 of the frame 10. The lugs 20 may be 70 suitably attached to the receptacle, for instance by means of a rim 36 secured thereon and provided with an operating handle 37 by which the receptacle may be shifted to disengage the lugs 20 from the frame 10. 75 The stirrer blade 33 is of less length than the blade 31 through which it extends but its ends engage the wall of the sieve or screen. This allows space for the fruit or other material placed within the screen and 80 the use of wooden blades prevents friction and the wearing of the sieves. These sieves are readily removable so that different sizes or characters thereof can be used and are supported against rotation upon the flange 85 of the frame. The stirrer is also removable so that the receptacle and sieve can be used as a colander or for any straining purpose.

90 In the operation of the invention it will be seen that the several parts are readily separable and the device supported for use by means of the handle carried by the frame. When the receptacle is engaged with the bayonet joints, it is drawn tightly to place which also prevents any movement of the 95 sieve and these parts may be held in such position by means of the latch for that purpose. The stirrer can be readily removed and replaced as shown in my Patent 100 #610,789. The invention is adapted for all 105 house-hold uses and particularly for breaking up fruits and for removing seeds and skins as well as for screening or smoothing vegetables, fruits or other materials. By removing the stirrer, the sieve may be used 110 for straining purposes and this sieve may be changed for another of suitable character for the work to be done. The invention, therefore, presents a simple, efficient and economically constructed form of press or colander.

Having described my invention and set

forth its merits, what I claim and desire to secure by Letters Patent is—

1. In a device of the class described, a receptacle provided with depending lugs, an annular frame having thereon coöperating bayonet slots to receive said lugs, and a sieve supported within said frame. 5
2. In a device of the class described, a receptacle provided with depending lugs, an annular frame having thereon coöperating bayonet slots to receive said lugs, a sieve supported within said frame, and a latch carried by said receptacle to engage said frame. 10
3. In a device of the class described, a receptacle provided with depending lugs, an annular frame having thereon coöperating bayonet slots to receive said lugs, a sieve supported within said frame, and a latch pivotally mounted upon said receptacle to engage one of the bayonet slots in said frame. 15
4. In a device of the class described, a receptacle provided at its lower portion with a series of depending lugs having inclined upper faces, a handle extended laterally from the lower portion of said receptacle, an annular supporting frame provided with a series of bayonet slots to receive said lugs, a flange within said frame, and a sieve provided at its upper portion with a rib to rest upon said flange. 20
5. In a device of the class described, a receptacle provided at its lower portion with a series of depending lugs having inclined upper faces, a handle extended laterally from the lower portion of said receptacle, an annular supporting frame provided with a series of bayonet slots to receive said lugs, a flange within said frame, a sieve provided at its upper portion with a rib to rest upon said flange, and a lateral projection from said sieve to enter a coöperating recess in said frame. 25

6. In a device of the class described, a receptacle, a sieve supported therefrom, a stirrer shaft pivotally mounted upon said receptacle and provided with bifurcated arms at its lower end, a stirrer blade mounted between said arms, and a second stirrer blade 50 extended laterally through an aperture in said arms and first mentioned blade. 45

7. In a device of the class described, a receptacle, a sieve supported therefrom, a stirrer shaft pivotally mounted upon said receptacle and provided with bifurcated arms at its lower end, a stirrer blade mounted between said arms, and a second stirrer blade 55 extended laterally through an aperture in said arms and first mentioned blade, said second stirrer blade being of less length than the first mentioned blade. 60

8. In a device of the class described, a receptacle provided at its lower portion with a band having a handle, a series of downwardly and outwardly disposed lugs carried by said band, a supporting frame having a plurality of lateral extensions each provided with a bayonet slot, and a sieve removably supported by said frame. 65

9. In a device of the class described, a receptacle provided at its lower portion with a band having a handle, a series of downwardly and outwardly disposed lugs carried by said band, a supporting frame having a plurality of lateral extensions each provided with a bayonet slot, a sieve removably supported by said frame, and a latch pivotally mounted upon said band and having a depending portion to enter an aperture in said frame. 70

In testimony whereof I affix my signature in presence of two witnesses.

EDWARD A. BEACH.
